(57) **CLAIM**

The ornamental design for a clamping connector, as shown and described.

DESCRIPTION

FIG. 1 is a front right view of a clamping connector showing my new design;

FIG. 2 is a bottom view thereof;

FIG. 3 is a front left view thereof;

FIG. 4 is a top view thereof;

FIG. 5 is a front right view of a single module of the clamping connector showing my new design;

FIG. 6 is a bottom view thereof;

FIG. 7 is a front left view thereof;

FIG. 8 is a top view thereof;

FIG. 9 is a front right view of a single module of the clamping connector with actuating levers removed showing my new design;

FIG. 10 is a bottom view thereof;

FIG. 11 is a front left view thereof;

FIG. 12 is a top view thereof;

FIG. 13 is a front right view of a clamping connector with actuating levers removed showing my new design;

FIG. 14 is a bottom view thereof;

FIG. 15 is a front left view thereof; and,

FIG. 16 is a top view thereof.

The claimed design is embodied in the appearance of the connector as it appears fully assembled in FIGS. 1 through 4. FIGS. 5 through 16 are shown in various stages of assembly in order to disclose aspects of the design that are not apparent from the views showing the fully assembled members.
